BLENDING OF TEXTILE FIBROUS MATERIALS

William Aldred Hunter, Stanhill, Accrington, and Frank Singleton, Accrington, England, assignors to T. M. M. (Research) Limited, Oldham, England

Original application August 6, 1953, Serial No. 302,914, now Patent No. 2,816,327, dated December 17, 1957. Divided and this application August 23, 1955, Serial No. 530,141

5 Claims. (Cl. 19—146)

This invention relates to a method of blending textile fibrous materials, i. e. the intimate mixture of fibres of different kinds, grades, qualities or other characteristics, as may be required to suit specific manufacturing requirements. This application is a division of our application Serial No. 302,914, filed August 6, 1953, now Patent No. 2,816,327, which as filed related to an improved method of and apparatus for blending different fibrous ingredients, the present application being directed to the said method.

The method herein described is an improvement upon methods heretofore customarily used, such as the so-called batch method, according to which a measured quantity of each of a number of different ingredients (which term is employed herein to denote fibres of different kinds, grades, qualities or the like) is delivered separately into a mixing chamber, either so as to form successive layers or piled in adjacent masses, the contents of the chamber then being mixed together until the whole mass is adjudged to have been sufficiently thoroughly intermingled. Such methods of blending are necessarily imperfect in that the production of anything approaching a homogeneous mixture of fibres cannot be assured, with the result that a large number of sliver doublings on subsequent machines is essential to produce yarns and fabric in which the blend is of satisfactory evenness. Another serious disadvantage of the "batch" method of blending arises from the fact that it is by its very nature intermittent and is therefore unsuited to a continuous mode of yarn production.

An object of the present invention is the provision of a method for blending different fibrous ingredients with such intimacy of admixture that the several ingredients are dispensed throughout the mass so nearly homogeneously that their individual characteristics are incapable of being detected save by careful analysis, thereby producing a yarn of fibres possessing a very high degree of uniformity. A further object is to provide homogeneous blending at such an early stage in the processing of the fibres that much less sliver doubling (for the purpose of blending) on subsequent machines is necessary and so that in some instances the number of subsequent machines may be reduced.

The method in accordance with this invention comprises the following steps: Feeding a plurality of ingredient materials to separate stations; compacting the material at each such station into sheet formation and advancing it forwardly therefrom at a measured rate while firmly gripping the same; and pulling material from the forward edge of each such sheet in the form of finely divided tufts and depositing the same upon a surface in such manner that the tufts from the several stations will be superposed. This may suitably be accomplished by depositing such tufts upon a member travelling past such stations successively, the speed of such travelling member being regulated relatively to the speeds of advance of the sheets from the several stations, so that the tufts will be deposited in superposed layers on such member. Fur-

2

ther, it is a preferable feature of the invention that the material is advanced from the several stations at speeds proportional to the proportions of the respective ingredient materials desired in the blend, or that the material is pulled from the forward edges of the advancing sheets at speeds proportional to the proportions of the several ingredients desired in the blend. The superposed layers of tufts may be conveyed forwardly for further operations.

Such a method may be carried on continuously or intermittently, and it will be observed that where a different kind, grade or quality of textile fibre is supplied to each station the effect will be to produce a blend in which the several ingredients are dispersed through the same quite homogeneously, a result which is attributable to the minuteness of the component tufts and the layered disposition of the same upon the surface upon which they are deposited.

The nature of the invention and the manner of carrying the same into effect is hereinafter more fully described with reference to the accompanying diagrammatic drawings, of which Fig. 1 is a schematic representation of a possible lay-out of a blending apparatus in relation to the apparatus by which it is supplied with different ingredient materials and the processing apparatus to which the blended mixture is delivered. Fig. 2 is a partly sectional elevation of one form of blending apparatus by which the method may be practised, and Fig. 3 is a perspective view thereof, the several driving gears and control circuits being omitted. Fig. 4 is a fragmentary sectional elevation depicting the upper parts of the measured-rate delivery units in a modified form of blending apparatus, and Fig. 5 is a detail view (drawn to a larger scale), illustrating the means employed to support and drive the condenser cages in the embodiment shown in Fig. 4, when viewed in the direction of the arrow, the surrounding case being removed.

In the lay-out illustrated in Fig. 1, each of the elements designated with the reference numeral 1 is a hopper feeder apparatus conveniently of the kind which forms the subject of United States Patent No. 2,666,956. Each such hopper feeder 1 is fed with one of the different ingredients of textile fibre which it is desired to blend, and each discharges its output into a pneumatic delivery duct 2 by which the fibres are conveyed in well-known fashion to the inlet of one of the measured-rate delivery units of the blending apparatus, which apparatus is indicated in Fig. 1 by the general reference numeral 3. The blend produced by said apparatus 3 is conveyed by pneumatic feed ducts 4 to one or more combined sets of hopper feeders 5 and intensive opening machines 6, preferably of the kind described in British Patent No. 650,157. The several hopper feeders 1, 1 should be adjusted so that the respective outputs discharged to the blending apparatus are of a uniform degree of openness, and thus in the most suitable condition for accurate metering.

Referring now to Fig. 2, it will be seen that the blending apparatus, indicated in Fig. 1 by the reference numeral 3, comprises a gang or assembly of measured-rate delivery units each of which includes a vertical gravity-feed trunk 7 at the head of which is a conventional rotary damped condenser cage 8. Said cage 8 is enclosed in a casing 9 which is entered by one of the pneumatic feed ducts 2 at the delivery end thereof, and all of the cages 8 are aspirated by means of fans 10, 10 to which connection is made with said cages by manifolds 11, 11, and the outlets of which are seen at 12, 12.

The otherwise open aperture at the base of each gravity-feed trunk 7 is controlled by a pair of metering rollers 13, 13, which are arranged to rotate in contrary directions so as to discharge the contents of the trunk at a rate governed by the speed of rotation of the rollers.

The several trunks 7 are assembled with their respective discharge points side-by-side in alignment, so that their respective metering rollers 13 are contained in a common horizontal plane and located at equally spaced intervals, above the upper horizontal course of a high-speed lattice conveyor 14, which is trained over driving rollers 15, 16, and with which there is associated a stripper element 17 by which material conveyed on the lattice is removed and directed into a receptacle which may take the form of the two-way distributor 18 shown in Fig. 1, which delivers to the hoppers 5 through the ducts 4. Said lattice bears closely-spaced cross-members 19 which are furnished with rows of spikes 20 inclined in the direction of travel of the lattice. Said spikes 20 should be disposed over the lattice surface in a uniformly staggered formation so as to avoid an unduly marked tracking effect. Furthermore, said spikes are set with their tips so close to the metering rollers 13 that by the impalement by the former of the fringe of material which projects between said rollers (as will be understood from the following description), said spikes are individually charged with minute tufts of fibres collected in turn from the fringe at the metered discharge point of each trunk 7.

The several moving parts of the apparatus are driven from two electric motors 21, 22. The shaft of the motor 21 is geared to one of the fans 10 by the belt 23, to the condenser cage driving rollers 24, 24 by the belts 25, 26, 27 and 28, and to the roller 15 of the conveyor lattice 14 by the belt 29. The shaft of the motor 22 is geared to the other of the fans 10 by the belt 30 and to one of each of the pairs of metering rollers 13, 13, through the belt 31, a pulley 32, a shaft 33, a pulley 34, a belt 35, a pulley 36, bevel gears 37, 38, a shaft 39 and individual belt-drives each of which includes a pulley 40, a belt 41, a variable-speed gear 42, a belt 43, a pulley 44, a shaft 45, and worm and worm-wheel gears 46, 47. The stripper 17 is conveniently geared to the roller 15 by spur-gearing 48, 49.

The delivery rate of the metering rollers, 13, 13, may be regulated separately at each unit by suitable adjustment of the variable-speed device 42.

The ingredient fibre received from the relative duct 2 by each cage 8 is condensed thereon and caused to be deposited within the trunk 7, where a substantially constant head is maintained by a photo-electric detector cell 50 which is sensitive to the instantaneous quantity of material in the trunk and which is connected by the line 51 to suitable electronic apparatus 52 serving to control a speed regulator (indicated conventionally at 53) associated with the delivery element of the hopper feeder 1, the arrangement being such that the rate of output of the hopper feeder is adjusted in accordance with the rate at which the fibre in the trunk 7 is being discharged by the metering rollers 13.

As has already been explained, the ingredient of each trunk 7 is discharged by the rollers 13 (at a rate determined by the setting of the variable speed device 42) so that it emerges in the form of a downwardly-depending sheet the fringe whereof is continuously combed by the tips of the spikes 20 of the lattice 14. The tufts of fibre which are impaled upon the lattice spikes 20 at each successive pair of metering rollers 13 compose a tenuous layer, so that when the spikes reach the stripping point at the conveyor roller 15 the lattice is carrying as many superposed layers of different ingredients as there are delivery units in the blending apparatus.

The composite mass of layered tufts is removed from the lattice by the stripper 17 and discharged into the distributor 18, whence the blended material is conducted to the hopper feeders 5 and intensive opening apparatus 6. (If desired, the hopper feeders 5 may be omitted, in which case the apparatus 6 is or are fed directly from the distributor 18.) It is convenient to provide in the distributor 18 an electrical contact 54 which is connected by a line 55 to electronic apparatus 56 serving to control

a clutch 57 which is inclined in the shaft 33 between the pulleys 32 and 34 in the drive of the metering rollers 13, 13, the arrangement being such that in the event of the contact 54 being operated, e. g. in the manner hereinafter described, the metering rollers 13, 13 in each trunk 7 will be arrested to discontinue delivery of material to the lattice. A photo-electric cell situated in each hopper feeder 5 is arranged to actuate suitable mechanism in the distributor 18 when the desired level of material in a feeder 10 is reached, so as automatically to cut off delivery from the distributor to that feeder. Actuation of both photo-cells is arranged to operate the contact 54 and to discontinue the supply to the distributor. The mechanism in the distributor 18 may be of known form incorporating electrically-controlled doors connected in circuit with the photo-cells in the hopper feeders.

The adjustment of the variable-speed units 42, by which it is possible to effect a variation in the gear-ratio between the pulleys 40 and 44 in the metering roller drive, enables the rate of delivery of each ingredient to the blending lattice 14 to be determined as may be necessary to provide any desired proportional admixture in the blend of materials discharged into the distributor 18. The several metered delivery units 7 may be calibrated for use with specific kinds of fibre, so that irrespective of its density the required proportion of an ingredient in a given blend may be achieved merely by regulating the speed of the metering rollers 13, 13 of the trunk 7 in question, by an adjustment of the relative unit 42.

In the modified embodiment illustrated in Figs. 4 and 5, the condenser cage 8 of each of the gravity-feed trunks 7 is arranged to float upon the surfaces of a pair of rubber-covered rollers 58 which impart the appropriate direction of rotation to the cage through spur gearing 59, 60 (Fig. 5). Said roller 58, of which the inner ones each serve partially to support two adjacent cages 8, constitute means for sealing the spaces between the cages and those parts of the casings lying between the ducts 2 and the trunks 7. The cages are provided with circumferential tongues 61 which are received in grooved rims 62 upon the shafts of the rollers 58 and which thereby serve to prevent endwise movement of the cages during their rotation.

With regard to the circuit of the photo-electric detector cells 50, and also that of the photo-electric cells 54 in the feeders 5, which are employed in both the aforedescribed embodiments, it is desirable to employ circuit apparatus in each case which will provide an asymmetrical delay in the operation of the control mechanism, in order (a) that by ensuring a rapid action of the control when the level of the material in the trunk or hopper falls, hunting may be prevented, and (b) to avoid the operation of the control merely by reason of the intermittent interruption of the energising light beam by the material falling into the trunk or hopper.

If desired, the hopper feeders 1 may be replaced by other appropriate opening machinery having a feed component which can be stopped and started intermittently by the photo-electric apparatus which is associated with the gravity-feed trunk 7 of the blending apparatus for the purpose of regulating the head of material in said trunk.

What we claim as our invention and desire to secure by Letters Patent is:

1. The method of blending a plurality of textile fibrous materials, consisting in stacking the materials in substantially vertically arranged stacks individually in successive order, feeding the materials from the bases of the stacks in loosely compacted sheet form, disintegrating said sheets by progressively pulling tufts from the bases of the stacks in succession in a horizontal direction to form layers one upon the other as they are fed horizontally from the stacks.

2. The method according to claim 1, wherein the materials are fed from the bases of the stacks at speeds pro-

portional to the proportions of the respectively ingredient materials desired in the blend.

3. The method according to claim 1, wherein the rates of feed of the materials into and from the stacks are so adjusted as to maintain approximately constant heads of material in each stack.

4. The method of blending a plurality of textile fibrous materials, consisting in stacking the materials in successive order in a plurality of stacks, feeding the materials from the bases of the stacks, disintegrating the leading edge of the sheets in succession by impaling in a different plane from said stacks finely divided tufts of material from each of said sheets in progression as they are fed from the bases of said stacks to thereby form superposed layers of the materials.

5. The method of blending and processing a plurality of textile fibrous materials consisting in subjecting a plurality of ingredient materials to separate preliminary opening operations, adjusting such operations so as to give to the opened material a substantially uniform degree of openness, stacking the ingredient materials in a

plurality of stacks, feeding the materials from the bases of the stacks, disintegrating the leading edge of the sheets in succession by impaling in a different plane from said stacks finely divided tufts of material from each of said sheets as they are fed from the stacks in succession to thereby form superposed layers of the materials.
